FLUSH TANK MECHANISM

John S. Milne, Chicago, Ill., assignor to Sears, Roebuck and Co., Chicago, Ill., a corporation of New York

Application July 12, 1944, Serial No. 544,488

10 Claims. (Cl. 4—13)

1

This invention relates to flush tank mechanism.

It is an object of my invention to provide a novel guide and support for a valve ball, whereby the up and down movement of said ball in service is facilitated.

A further object resides in the provision of a valve ball support and guiding means in which substantially fewer parts are involved than has heretofore been the case.

An additional object is to provide a flush tank with an integral ball valve seat.

Another object is to provide a valve ball trip lever which is combined with the flush bowl in a convenient position to be readily operated by foot or by hand.

It is also an object to provide a sealed valve ball control lever mounting.

Further objects and advantages of my invention will appear as the description proceeds.

The invention will be better understood upon reference to the following description and the accompanying drawing, in which:

Fig. 1 is a fragmentary vertical sectional view through a water closet flushing mechanism embodying features of my invention.

Fig. 2 is a fragmentary sectional view taken as indicated by line 2—2 in Fig. 1.

Fig. 3 is a plan sectional view taken as indicated by the line 3—3 in Fig. 2.

Fig. 4 is a fragmentary plan sectional view taken as indicated by the line 4—4 in Fig. 1.

Fig. 5 is an enlarged fragmentary sectional view similar to a portion of Fig. 1 but with an additional part in section to show additional details.

Fig. 6 is a view similar to Fig. 1 but of a modified construction.

Fig. 7 is a fragmentary sectional view taken as indicated by the line 7—7 in Fig. 6.

Fig. 8 is a fragmentary sectional view taken as indicated by the line 8—8 in Fig. 6.

Fig. 9 is a sectional view similar to a part of Fig. 6 but with an additional part in section to show further details.

Referring now more particularly to the drawing, there is shown at 10 a vitreous or other suitable flush tank having an overflow tube 12 which may be integral with the tank 10, and a discharge orifice 14 adapted to communicate with the tube 12. The tank 10 is supported on the flange 16 of a gasket sleeve 18 which in turn rests on and fits within the inlet 20 of a bowl 22, the water from the discharge orifice 14 gaining access to the interior of the bowl 22 through said sleeve.

2

The valve ball unit is indicated generally at 23 and may be of any suitable construction. As disclosed herein for the purpose of illustration only, the ball itself may be a hollow rubber member 24 having a truncated substantially hemispherical flexible valve portion 26 adapted to cooperate with a spherically or otherwise tapered valve seat 28 which is preferably a surface of the tank 10 itself. The ball member 24 has an opening 30 to enhance the flexibility of said portion and to admit a stem 32 threaded as at 34 or otherwise suitably anchored to the upper end portion 36 of the ball member.

The stem 32 preferably extends down substantially below the gasket sleeve 18 in the bowl 22, when the valve is closed, and is telescopically received in a sleeve 38 which is adapted also to extend through the opening 30 and into the interior of the ball member 24. A sleeve guide 40 surrounding and in sliding engagement with the exterior of the sleeve 38 is held relatively stationary. To that end, the guide 40 is formed on or secured to a bar or arm 42 which extends into the discharge end 44 of the overflow tube 12 and is clamped in selected positions of adjustment by a bolt or screw 45 whose head is disposed outside of the tank 10 and engages a sealing washer 46 which prevents leakage of water through the bolt hole 48 and whose other end is threaded in the arm 42. The bolt hole 48 is elongated in the direction in which the arm 42 extends in order that the sleeve guide 40 may be adjusted to center the sleeve 38 so that it will not interfere with the proper seating of the ball member 24 on the valve seat 28. Adjustment of the sleeve guide 40 transverse to said direction can be effected by loosening the bolt 45 and turning the arm 42 to the desired extent about the axis of the bolt, which thereafter can be tightened.

40 The sleeve 38 has a plate-like substantially horizontal base 50 providing a bottom bearing surface 52 for engagement with a spherically or otherwise convexly rounded surface 54 on the driven end or arm 56 of a trip lever 58. The driven arm 56 is disposed within the bowl 22, and is riveted as at 60 or otherwise rigidly connected to a rock shaft 62 which is supported in a bearing sleeve 64 passing through a vertical wall 66 of the bowl 22. A gasket washer 68 held under compression between the bowl wall 66 and a nut 70 on the threaded outer end of the bearing sleeve 64 prevents leakage of water between said sleeve and the bowl. A removable keeper ring 72 projecting from a circumferential groove in the rock

shaft 62 holds the shaft and sleeve 64 in the desired relation.

The shaft 62 extends outward substantially beyond the bearing sleeve 64 and is connected to rotate with the actuating handle or driving arm 74 of the trip lever 58. To this end, the arm 74 may have a socket 76 in which the end 78 of the shaft is received, the parts being held in assembly by suitable means such as a screw 80. The socket 76 and end 78 may be square or otherwise shaped to preclude relative rotation. In order to prevent leakage of water between the shaft 62 and the sleeve 64, I provide a gasket such as a rubber or the like sleeve or ferrule 82 having an external flange 84 at one end which is compressed against the outer end of the sleeve 64 as by a gland nut 86 threaded on the sleeve 64, and, at the other end, an internal flange 88 which is compressed between a shoulder 89 in the hub 90 of the driving lever arm 74 and a collar 92 non-rotatably fitting the shaft end 78 and abutting the shaft shoulder 93, the flange 88 being held under compression by the screw 80.

The actuating arm 74 has at its free end a flat surface 94 of substantial area to be engaged by the hand or foot for facilitating operation of the trip lever. The trip lever is normally substantially in the position shown in Fig. 1, with all or a substantial part of its handle area 94 projecting beyond the flange 96 of the bowl as seen in Fig. 2, to render the same readily accessible to the foot or hand.

Provision is made for movement of the trip lever through approximately $\frac{1}{2}$ of a turn, during which the ball valve member 24 is lifted a substantial distance off the valve seat 28 so that the ball member will float and not be reseated by the suction, permitting the flow of water from the flush tank 10 through the tank outlet 14 and into the bowl 22 to flush the same. During this rotation of the trip lever the rubber seal or ferrule 32 is subjected to a slight twist, but the resistance it offers under these circumstances is negligible, particularly inasmuch as its diameter is substantially greater than that of the portion of the shaft 62 which it surrounds, so that clearance for diametral contraction of the ferrule upon twisting thereof is provided. As the flushing proceeds, the ball valve member 24 and sleeve 38 descend, causing the trip lever 58 to return to its normal position, and the rubber sleeve resumes its normal shape, shown in Fig. 1. The handle arm 74 may be lighter than the driven arm 58, in order to insure the automatic return of the trip lever to the Fig. 1 position, but in any event the weight of the arm 74 should be less than that of the arm 58 and sleeve 38 combined to insure that result.

In view of the curvature of the surface 54 on the driven arm of the trip lever, the lifting force exerted on the sleeve 38 upon operation of the trip lever is in a direction substantially parallel to the axis of said sleeve, so that friction between said sleeve and the guide 40 is minimized. Moreover, in view of the fact that the sleeve 38 receives such a relatively long portion of the valve ball stem 32, the ball is properly guided in its movements so that it always comes to rest in sealing engagement with the valve seat 28.

To preclude any possibility that the ball member might be thrown upward out of control, I provide a stop 100 which is suitably held as by bolt and nut means 102 on a lug 104 extending from any suitable part of the flush tank 10, such as the overflow tube 12. Upon loosening of the holding means 102, the stop 100 may be adjusted

to the desired position over the axis of the ball member. When it is desired to remove the ball member for any reason the bolt and nut means 102 may be loosened and the stop 100 swung around to an out-of-the-way position.

A modified construction is shown in Fig. 6, wherein the discharge orifice 110 and ball valve seat 112 are formed in a fitting 114 passing through a bottom opening 116 in the tank 118. The fitting has a tubular branch 120 serving to conduct water from the overflow tube 122 supported thereby to the discharge orifice 110. The fitting is held in leak-proof assembly with the tank by means of a rubber or other suitable gasket 124 held under compression against the upper rim 126 of the tank opening 116 by a flange 128 on the fitting and a nut 130 threaded on the fitting and engaging the bottom of the tank. The nut 130 is seated on a rubber or other suitable gasket 132 about the fitting 104 and in the inlet 20 of the bowl 22.

Preferably cast integral with the fitting 114 is a spider 134 which does not interfere with the water discharge and has a hub 136 serving as a guide for the ball stem sleeve 38. The operation of this structure will be evident upon inspection and in view of the description above the reference to Fig. 1.

A stop arm 140 about the overflow tube 122 and having the functions of the stop 100 is adapted to be held in adjusted positions as by a set screw 142, and may be adjusted vertically also.

The ball member 24 may be adapted for conventional use also by reason of the additional threaded hole 144 opening upwardly.

Various modifications may suggest themselves to those skilled in the art without departing from the spirit of my invention, and, hence, I do not wish to be restricted to the specific form shown or uses mentioned, except to the extent indicated in the appended claims, which are to be interpreted as broadly as the state of the art will permit.

I claim:

45. 1. A water closet flushing mechanism comprising a bowl, a flush tank mounted thereon and communicating by gravity therewith, a valve for controlling the gravity flow of water from said tank to said bowl, and a trip lever rotatively mounted on said bowl and having an arm within said bowl for opening said valve and a handle outside said bowl for actuation by hand or foot.

50. 2. A water closet flushing mechanism comprising a bowl, a flush tank mounted thereon and communicating therewith, a valve for controlling the flow of water from said tank to said bowl, a trip lever rotatively mounted on said bowl and having an arm within said bowl for opening said valve and handle outside said bowl for actuation by hand or foot, said valve including a ball member disposed to be raised off the valve seat pursuant to operation of said trip lever, and means for limiting the extent of rising movement of said ball member.

55. 3. A water closet flushing mechanism comprising a bowl, a flush tank mounted thereon and communicating therewith, a valve for controlling the flow of water from said tank to said bowl, a trip lever rotatively mounted on said bowl and having an arm within said bowl for opening said valve and a handle outside said bowl for actuation by hand or foot, said valve including a ball member adapted to be raised off the valve seat by said trip lever, and a stem secured to said ball member and extending a substantial distance

downwardly therefrom, and means for constraining said ball member to movement coaxially with said stem, said means comprising a sleeve telescoping a substantial portion of the length of said stem and providing a bottom abutment for said stem, the bottom of said sleeve affording a bearing surface engaged by said lever upon tripping thereof, and means guiding said sleeve.

4. A flush tank having a discharge orifice and valve seat, a ball cooperating with said seat and having a depending stem, a sleeve receiving said stem, means for guiding said sleeve in reciprocatory movement, means limiting upward movement of said sleeve relative to said ball, said sleeve having a bottom bearing surface, and a trip lever for raising said ball off said seat, said lever having a convex upper surface in sliding engagement with said bottom surface on said sleeve, and a toilet bowl having a portion enclosing said trip lever.

5. A flush tank, a bowl over which said tank is supported, a valve controlling flow from said tank to said bowl, and a trip lever for said valve, said lever having a driven arm within said bowl, a handle arm outside said bowl, and a rock shaft to which said arm and handle are joined, said wall having a transverse hole therethrough, a bearing sleeve disposed in said hole, and liquid sealing means associated with said bearing sleeve.

6. In a toilet flushing mechanism, a toilet bowl having a wall with a hole therethrough, a valve trip lever comprising a shaft in said hole and lever arms connected to the respective ends of said shaft inside and outside said bowl, a relatively stationary shaft journaling member in said hole, means preventing escape of liquid between said wall and said journaling member, and means preventing escape of liquid between said journaling member and said shaft.

7. A flush tank having a discharge orifice and a ball valve seat, a vertically movable ball cooperating with said seat, means for guiding said ball in its vertical movement away from and toward said seat comprising a vertically slideable member and a single fixed member journaling the latter, means for adjusting said fixed guiding means in a plurality of directions so as to insure the establishment of the proper operative relation between said ball and seat, said guiding means confining said ball to substantially vertical movement irrespective of the adjustment of

said guiding means, the guide and adjusting means being disposed below the ball, and actuating means for tripping said ball off said seat.

8. A flush tank having a discharge orifice and a ball valve seat, a vertically movable ball cooperative with said seat, means for guiding said ball in its vertical movement away from and toward said seat, said guiding means consisting of a vertically slideable member engaging said valve and a single fixed member slideably engaging said slideable guide member to insure accurate vertical movement of the valve and to insure proper operative relation between the ball and seat, all of said parts being disposed in the bottom of said flush tank, and actuating means for tripping said ball off said seat.

9. A combination as defined in claim 8 wherein the actuating means comprises a lever cooperative with said slideable guide means, said lever having wiping engagement with said slideable guide means transversely of the latter's motion.

10. A combination as defined in claim 8 wherein the actuating means comprises a lever cooperative with said slideable guide means, said lever having wiping engagement with said slideable guide means transversely of the latter's motion, and a flush bowl enclosing said lever and slideable guide means.

JOHN S. MILNE.
